UNITED STATES PATENT OFFICE

HARRY L. MYERS, OF TOLEDO, OHIO, ASSIGNOR TO THE AMERICAN FLOOR SURFACING MACHINE COMPANY, OF TOLEDO, OHIO, A CORPORATION OF OHIO

DESIGN FOR A BENCH SANDER

Application filed October 6, 1930. Serial No. 37,156. Term of patent 14 years.

To all whom it may concern:

Be it known that I, HARRY L. MYERS, a citizen of the United States, residing at Toledo, in the county of Lucas and State of Ohio, have invented a new, original, and ornamental Design for a Bench Sander, of which the following is a specification, reference being had to the accompanying drawing, forming part thereof.

Figure 1 is a side elevational view of a surfacing machine constructed in accordance with the inventive conception and used primarily as a bench sander.

Figure 2 is an end view of the structure observed in Figure 1 looking at the same in a direction from right to left.

Figure 3 is a view like Figure 1, observing the opposite side of said machine.

Figure 4 is an end view of the structure seen in Figure 1 looking at the same from left to right.

I claim:

The ornamental design for a bench sander as shown and described.

HARRY L. MYERS.
